UNITED STATES PATENT OFFICE.

JASPER A. WOODWORTH, OF KALAMAZOO, MICHIGAN.

PORTABLE WINDLASS.

SPECIFICATION forming part of Letters Patent No. 794,765, dated July 18, 1905.

Application filed September 22, 1904. Serial No. 225,502.

To all whom it may concern:

Be it known that I, JASPER A. WOODWORTH, a citizen of the United States, residing at the city of Kalamazoo, county of Kalamazoo, State 5 of Michigan, have invented certain new and useful Improvements in Portable Windlasses, of which the following is a specification.

This invention relates to improvements in portable windlasses.

10 The objects of this invention are, first, to provide an improved portable windlass by which buildings and like heavy objects which it is desired to move considerable distances may be moved with comparative ease and rapidity; second, to provide an improved portable windlass which is comparatively simple in structure and in operation and at the same time is capable of performing very heavy work.

20 Further objects and objects relating to structural details will definitely appear from the detailed description to follow.

I accomplish the objects of my invention by the devices and means described in the following specification.

25 The invention is clearly defined, and pointed out in the claims.

A structure embodying the features of my invention is clearly illustrated in the accompanying drawings, forming a part of this specification, in which—

30 Figure 1 is a side elevation view of my improved portable windlass, portions of the frame being broken away to show the arrangement of the parts. Fig. 2 is a plan view thereof. Fig. 3 is a detail sectional view showing the manner of securing the cables, taken on a line corresponding to line 3 3 of Fig. 1.

40 In the drawings similar letters of reference refer to similar parts in the several views.

Referring to the drawings, A is the supporting-frame. This frame A is provided with suitable carrying runners or shoes A'.

45 The rear portion of the frame is provided with a bottom which serves as a scraper or pick-up for the anchor-chain E. This scraper or pick-up is preferably made up of slat-like cross-pieces a a', the forward cross-piece a being shaped to form a scraper-blade. The ob-

ject of this scraper or pick-up for the anchor-chain will fully appear from the detailed description to follow.

The cross-pieces a a' are spaced apart to allow the dirt picked up thereby to fall through to the ground as the windlass is moved forward. A transversely-arranged axle B is supported in suitable bearings carried by the frame A. Centrally arranged on this axle is a driving-wheel B', having a peripheral groove 55 therein adapted to receive the draft or power cable C. The axle B at each side of the wheel B' serves as winding-drums for the tackle rope or cable L. The draft-chain D is connected by the chains D' to the forward ends of the 60 longitudinally-arranged rods h. These rods are secured to the sides of the frame A.

The draft-chain D is provided with a claw-shaped grappling-hook d at its forward end. This hook is adapted to engage the anchor-chain E, the same being shown connected therewith in Fig. 1 and disconnected therefrom in Fig. 2. The anchor-chain E is secured to the anchor-posts, as e, by the cross-chain E'. The anchor-chain E is connected 75 to the cross-chain E' by means of the pulley e' at its forward end. This insures an even pull on the cross-chain and a direct pull for the windlass, avoiding the necessity of carefully locating the anchor-posts. By the use 80 of the cross-chain E' the posts may be located at the sides of the street or roadway or secured to trees or the like along the highway or street. This is of particular advantage on paved streets or the like, where it is not expedient to drive the anchor-posts into the 85 central part of the street.

The driving or power cable C is adapted to be wound in the peripheral groove of the wheel B'. This cable C is provided with a 90 centrally-located guide c on the cross-piece c' of the frame. This guide being located directly in front of the wheel B' guides the cable thereon in winding and prevents its being drawn over the edge thereof in operating 95 the device.

A tackle consisting of a pair of pulley-blocks F and G is provided. The block F is secured to the rear ends of the rods h by a pair of chains H, which are connected to the 100

- eyebolts *h*' in the forward end of the pulley. The block *G* is connected by the chain *I* to the building or object to be moved, the same being illustrated herein in conventional form.
- 5 The eyebolt *i* for securing the chain *I* to the block *G* is centrally arranged thereon. The blocks *F* and *G* are of peculiar construction, particularly adapted for use in this relation. These blocks *F* and *G* are of considerable 10 width, and the sheaves *f*' and *g* and *g*' are arranged at the sides thereof, so that the tackle-cable *L* is guided onto the winding-drums at each side of the driving-wheel *B*. The sheave *f* of the block *F* is arranged on the rear end 15 thereof. The tackle-cable *L* is passed over this sheave, thence over the sheaves *g*' of the block *G*, thence over the sheaves *f*' of the block *F*, and back over the sheave *g* of the block *G*. They are then passed forwardly 20 and secured to the winding-drums of the axle *B*. With the blocks thus formed the tackle-rope *L* is positively prevented from becoming tangled. The block *F* is secured by the chains *H*, so that it always maintains its 25 proper position. The sheaves of the pulleys are arranged so that there is no danger of the tackle becoming twisted, and the strain on the tackle-cable is reduced to a minimum. The blocks *F* and *G* are of sufficient width so 30 that the tackle-cable *L* is, as before stated, delivered to the winding-drums of the shaft *B* in the proper relation at each side of the wheel *B*'.
- To prevent the tackle-cables being drawn 35 across the edges of the wheel *B* in operation in the event of side draft, I arrange a guide-roller *M* between the same and opposite the wheel *B*'. This roller *M* is of such diameter as to guide the tackle-cables *L* to each side of 40 the wheel. The wheel *B* is provided with ratchet-teeth *b*', and a pivoted pawl *b*, adapted to engage these teeth, is provided.
- I secure the driving and the tackle cables in a peculiar manner, which, while very 45 secure, enables their being quickly attached or detached. I accomplish this by boring three holes through the wheel for each cable to be secured. The end of the cable to be secured is then passed through these holes and its end 50 inserted under the loop *l* thus formed in the cable, so that it is clamped between the loop and the face of the wheel. This secures the cables, so that while they are securely retained there is no possibility of their becoming un- 55 done under tension. At the same time they can be readily released should occasion require without cutting, as is likely to be necessary in case they have been secured by means of knots.
- 60 In operation the tackle is connected to the object to be moved, the tackle-cables being unwound from the drums and the driving or power cable wound upon the wheel *B*'. The anchor-chain *E* is properly secured and the 65 grappling-hook *d* is engaged therewith. The

anchor-chain *E* is of considerable length and is preferably located in the first instance so that the grappling-hook *d* is engaged with the rear end thereof. With the parts thus connected power is applied to the driving-cable 70 *C*, preferably horse-power. This drives the winding-drums and through the tackle connection with the building described moves the building forward. When the tackle is collapsed—that is, closed up as far as possible—75 the windlass is moved forward, preferably by hitching to the draft-chain *D*, until the tackle is extended. This drives the wheel *B*' backwardly, thereby winding up the driving-cable on the wheel *B*'. The hook *b* is again engaged 80 with the anchor-chain, and the operation is repeated. As the windlass is drawn forward the anchor-chain is picked up by the scraper or pick-up therefor on the windlass. This carries the chain along, so that it does not interfere with the carrying-rollers of the building or object being moved. By thus arranging the parts I am enabled to move very heavy objects very rapidly. The anchor-chain *E* is 85 preferably of considerable length, as it requires less frequent resetting of the anchor-posts, and consequently there is a large amount of time saved. With the comparatively long anchor-chain the windlass can be reset a number of times without changing the anchor- 90 posts, and, as before stated, it is only necessary in resetting the same to transfer the power to hitch from the driving-cable to the draft-chain *D*'. This resetting also winds up 95 the driving-cable. 100

By connecting the draft-chains *D* and the tackle-securing chains *H* to the ends of the rod *h* very little strain is placed upon the frame of the windlass when in operation. The strain upon the axle *B* is also minimized by 105 the arrangement of parts as I have illustrated and described. The structure may therefore be made of comparatively light material and still be strong and durable. With my improved windlass comparatively heavy objects 110 may be rapidly and easily moved. I have illustrated and described the same in detail in the form preferred by me on account of its structural simplicity and economy, although I am aware that the same might be varied considerably in structural details without departing 115 from my invention.

Having thus described the invention, what is claimed as new, and desired to be secured by Letters Patent, is— 120

1. In a windlass, the combination of a supporting-frame; runners or shoes therefor; a scraper in the bottom of said frame; a transversely-arranged axle; a driving-wheel, having a groove in the periphery thereof, mounted on said axle; winding-drums on the axle to each side of said wheel; a driving-cable for said driving-wheel; a guide for said cable supported on said frame opposite said wheel; a draft-chain; an anchor-chain; means for de- 125 130

tachably connecting said chains; a tackle consisting of a pulley-block F having a sheave f on its rear end and a pair of sheaves f' at the sides thereof; a pulley-block G having sheaves g and g' arranged in pairs at the sides thereof; a tackle-cable L passed over said sheave f of the block F, thence rearwardly over the sheaves g' of the block G, thence forwardly over the sheaves f' of the block F, thence rearwardly over the sheaves g of the block G, and thence forwardly to the winding-drums at each side of the driving-wheel, said pulley-blocks being of a greater width than said wheel, all coacting for the purpose specified.

2. In a windlass, the combination of a supporting-frame; runners or shoes therefor; a scraper in the bottom of said frame; a transversely-arranged axle; a driving-wheel, having a groove in the periphery thereof, mounted on said axle; winding-drums on the axle to each side of said wheel; a driving-cable for said driving-wheel; a draft-chain; an anchor-chain; means for detachably connecting said chains; a tackle consisting of a pulley-block F having a sheave f on its rear end and a pair of sheaves f' at the sides thereof; a pulley-block G having sheaves g and g' arranged in pairs at the sides thereof; a tackle-cable L passed over said sheave f of the block F, thence rearwardly over the sheaves g' of the block G, thence forwardly over the sheaves f' of the block F, thence rearwardly over the sheaves g of the block G, and thence forwardly to the winding-drums at each side of the driving-wheel, said pulley-blocks being of a greater width than said wheel, all coacting for the purpose specified.

3. In a windlass, the combination of a supporting-frame; runners or shoes therefor; a scraper in the bottom of said frame; a transversely-arranged axle; a driving-wheel, having a groove in the periphery thereof, mounted on said axle; winding-drums on the axle to each side of said wheel; a driving-cable for said driving-wheel; a guide for said cable supported on said frame opposite said wheel; a draft-chain an anchor-chain; means for detachably connecting said chains; a tackle consisting of a pulley-block F having a sheave f on its rear end and a pair of sheaves f' at the sides thereof; a pulley-block G having sheaves g and g' arranged in pairs at the sides thereof; and a tackle-cable L passed over said sheave f of the block F, thence rearwardly over the sheaves g' of the block G, thence forwardly over the sheaves f' of the block F, thence rearwardly over the sheaves g of the block G, and thence forwardly to the winding-drums at each side of the driving-wheel, said pulley-blocks being of a greater width than said wheel, all coacting for the purpose specified.

block G, and thence forwardly to the winding-drums at each side of the driving-wheel, said pulley-blocks being of a greater width than said wheel, all coacting for the purpose specified.

4. In a windlass, the combination of a supporting-frame; runners or shoes therefor; a scraper in the bottom of said frame; a transversely-arranged axle; a driving-wheel, having a groove in the periphery thereof, mounted on said axle; winding-drums on the axle to each side of said wheel; a driving-cable for said driving-wheel; a draft-chain; an anchor-chain; means for detachably connecting said chains; a tackle consisting of a pulley-block F having a sheave f on its rear end and a pair of sheaves f' at the sides thereof; a pulley-block G having sheaves g and g' arranged in pairs at the sides thereof; and a tackle-cable L passed over said sheave f of the block F, thence rearwardly over the sheaves g' of the block G, thence forwardly over the sheaves f' of the block F, thence rearwardly over the sheaves g of the block G, and thence forwardly to the winding-drums at each side of the driving-wheel, said pulley-blocks being of a greater width than said wheel, all coacting for the purpose specified.

5. In a windlass, the combination of a supporting-frame; runners or shoes therefor; a transversely-arranged axle; a driving-wheel, having a groove in the periphery thereof, mounted on said axle; winding-drums on the axle to each side of said wheel; a driving-cable for said driving-wheel; a guide for said cable supported on said frame opposite said wheel; a draft-chain; an anchor-chain; means for detachably connecting said chains; a tackle consisting of a pulley-block F having a sheave f on its rear end and a pair of sheaves f' at the sides thereof; a pulley-block G having sheaves g and g' arranged in pairs at the sides thereof; a tackle-cable L passed over the said sheave f of the block F, thence rearwardly over the sheaves g' of the block G, thence forwardly over the sheaves f' of the block F, thence rearwardly over the sheaves g of the block G, and thence forwardly over the sheaves f' of the block F, thence rearwardly over the sheaves g of the block G, and thence forwardly to the winding-drums at each side of the driving-wheel, said pulley-blocks being of a greater width than said wheel, and a vertical guide-roller arranged on said frame opposite said driving-wheel to prevent the tackle-cables from being drawn across the edges of said wheel, all coacting for the purpose specified.

6. In a windlass, the combination of a supporting-frame; runners or shoes therefor; a transversely-arranged axle; a driving-wheel, having a groove in the periphery thereof, mounted on said axle; winding-drums on the axle to each side of said wheel; a driving-cable for said driving-wheel; a draft-chain; an anchor-chain; means for detachably connecting said chains; a tackle consisting of a pulley-block F having a sheave f on its rear end and

a pair of sheaves f' at the sides thereof; a pulley-block G having sheaves g and g' arranged in pairs at the sides thereof; a tackle-cable L passed over said sheave f' of the block F, thence 5 rearwardly over the sheaves g' of the block G, thence forwardly over the sheaves f' of the block F, thence rearwardly over the sheaves g of the block G, and thence forwardly to the winding-drums at each side of the driving- 10 wheel, said pulley-blocks being of a greater width than said wheel; and a vertical guide-roller arranged on said frame opposite said driving-wheel to prevent the tackle-cables from being drawn across the edges of said 15 wheel, all coacting for the purpose specified.

7. In a windlass, the combination of a supporting-frame; runners or shoes therefor; a transversely-arranged axle; a driving-wheel, having a groove in the periphery thereof, 20 mounted on said axle; winding-drums on the axle to each side of said wheel; a driving-cable for said driving-wheel; a guide for said cable supported on said frame opposite said wheel; a draft-chain; an anchor-chain; means for detachably connecting said chains; a tackle consisting of a pulley-block F having a sheave f on its rear end and a pair of sheaves f' at the sides thereof; a pulley-block G having sheaves g and g' arranged in pairs at the sides thereof; 25 and a tackle-cable passed over said sheave f of the block F, thence rearwardly over the sheaves g' of the block G, thence forwardly over the sheaves f' of the block F, thence rearwardly over the sheaves g of the block G, and 30 thence forwardly to the winding-drums at each side of the driving-wheel, said pulley-blocks being of a greater width than said wheel; all coacting for the purpose specified.

8. In a windlass, the combination of a supporting-frame; runners or shoes therefor; a transversely-arranged axle; a driving-wheel, having a groove in the periphery thereof, 40 mounted on said axle; winding-drums on the axle to each side of said wheel; a driving-cable for said driving-wheel; a draft-chain; an anchor-chain; means for detachably connecting said chains; a tackle consisting of a pulley-block F having a sheave f on its rear end and a pair of sheaves f' at the sides thereof; a pulley-block G having sheaves g and g' arranged in pairs at the sides thereof; and a tackle-cable L passed over said sheave f of the block F, thence rearwardly over the sheaves g' of the block G, thence forwardly over the sheaves 45 g of the block G, and thence forwardly to the winding-drums at each side of the driving-wheel, said pulley-blocks being of a greater width than said wheel, all coacting for the purpose specified.

60 9. In a windlass, the combination of a supporting-frame; a scraper carried thereby; a transversely-arranged axle; a driving-wheel, having a groove in the periphery thereof, 65 mounted on said axle; winding-drums on said axle to each side of said wheel; a driving-cable for said driving-wheel; draft-rods secured to the sides of said frame; a draft-chain secured to the forward ends of said draft-rods; means for detachably connecting said chains;

for said driving-wheel; a guide for said cable supported on said frame opposite said wheel; draft-rods secured to the sides of said frame; a draft-chain secured to the forward ends of said draft-rods; means for detachably connecting 70 said chains; an anchor-chain; a cross-chain to which said anchor-chain is secured by suitable pulleys; a tackle consisting of a pair of pulley-blocks, one of which is connected to the rear ends of said draft-rods and the other to the 75 object to be moved; a tackle-cable; and a vertical guide-roller arranged in said frame opposite said driving-wheel to prevent the tackle-cables from being drawn across the edges of said wheel, all coacting for the purpose specified. 80

10. In a windlass, the combination of a supporting-frame; a scraper carried thereby; a transversely-arranged axle; a driving-wheel, having a groove in the periphery thereof, 85 mounted on said axle; winding-drums on said axle to each side of said wheel; a driving-cable for said driving-wheel; draft-rods secured to the sides of said frame; a draft-chain secured to the forward ends of said draft-rods; means for detachably connecting said chains; an anchor-chain; a cross-chain to which said anchor-chain is secured by suitable pulleys; a tackle consisting of a pair of pulley-blocks, one of which is secured to the rear ends of 90 said draft-rods and the other to the object to be moved; a tackle-cable; and a vertical guide-roller arranged in said frame opposite said driving-wheel to prevent the tackle-cables from being drawn across the edges of 95 said wheel, all coacting for the purpose specified. 100

11. In a windlass, the combination of a supporting-frame; a scraper carried thereby; a transversely-arranged axle; a driving-wheel, having a groove in the periphery thereof, 10 mounted on said axle; winding-drums on said axle, to each side of said wheel; a driving-cable for said driving-wheel; a guide for said cable supported on said frame opposite said wheel; draft-rods secured to the sides of said frame; a draft-chain secured to the forward ends of said draft-rods; means for detachably connecting said chains; an anchor-chain; a cross-chain to which said anchor-chain is secured by suitable pulleys; a tackle consisting 11 of a pair of pulley-blocks, one of which is connected to the rear ends of said draft-rods and the other to the object to be moved; a tackle-cable; all coacting for the purpose specified. 112

12. In a windlass, the combination of a supporting-frame; a scraper carried thereby; a transversely-arranged axle; a driving-wheel, having a groove in the periphery thereof, 12 mounted on said axle; winding-drums on said axle to each side of said wheel; a driving-cable for said driving-wheel; draft-rods secured to the sides of said frame; a draft-chain secured to the forward ends of said draft-rods; means for detachably connecting said chains; 13

an anchor-chain; a cross-chain to which said anchor-chain is secured by suitable pulleys; and a tackle consisting of a pair of pulley-blocks, one of which is connected to the rear 5 ends of said draft-rods and the other to the object to be moved, all coacting for the purpose specified.

13. In a windlass, the combination of a supporting-frame; a transversely-arranged axle; 10 a driving-wheel, having a groove in the periphery thereof, mounted on said axle; winding-drums on said axle to each side of said wheel; a driving-cable for said driving-wheel; a guide for said cable supported on said frame 15 opposite said wheel; draft-rods secured to the sides of said frame; a draft-chain secured to the forward ends of said draft-rods; means for detachably connecting said chain; an anchor-chain; a cross-chain to which said anchor- 20 chain is secured by suitable pulleys; a tackle consisting of a pair of pulley-blocks, one of which is connected to the rear ends of said draft-rods and the other to the object to be moved; a tackle-cable; and a vertical guide- 25 roller arranged in said frame opposite said driving-wheel to prevent the tackle-cables from being drawn across the edges of said wheel, all coacting for the purpose specified.

14. In a windlass, the combination of a supporting-frame; a transversely-arranged axle; 30 a driving-wheel, having a groove in the periphery thereof, mounted on said axle; winding-drums on said axle to each side of said wheel; a driving-cable for said driving-wheel; draft-rods secured to the sides of said frame; a draft-chain secured to the forward ends of said draft-rods; means for detachably connecting said chains; an anchor-chain; a cross-chain to which said anchor-chain is secured by 35 suitable pulleys; a tackle consisting of a pair of pulley-blocks, one of which is connected to the rear ends of said draft-rods and the other to the object to be moved; a tackle-cable; and a vertical guide- 40 roller arranged in said frame opposite said driving-wheel to prevent the tackle-cables from being drawn across the edges of said wheel, all coacting for the purpose specified.

15. In a windlass, the combination of a supporting-frame; a transversely-arranged axle; 45 a driving-wheel, having a groove in the periphery thereof, mounted on said axle; winding-drums on said axle to each side of said wheel; a driving-cable for said driving-wheel; a guide for said cable supported on said frame opposite said wheel; draft-rods secured to the sides of said frame; a draft-chain secured to the forward ends of said draft-rods; means for detachably connecting said chains; an anchor- 50 chain; a cross-chain to which said anchor-chain is secured by suitable pulleys; a tackle consisting of a pair of pulley-blocks, one of which is connected to the rear ends of said draft-rods, and the other to the object to be

moved; and a tackle-cable, all coacting for the 65 purpose specified.

16. In a windlass, the combination of a supporting-frame; a transversely-arranged axle; a driving-wheel, having a groove in the periphery thereof, mounted on said axle; winding-drums on said axle, to each side of said wheel; a driving-cable for said driving-wheel; draft-rods secured to the sides of said frame; a draft-chain secured to the forward ends of said draft-rods; means for detachably connecting said chains; an anchor-chain; a cross-chain to which said anchor-chain is secured by suitable pulleys; a tackle consisting of a pair of pulley-blocks, one of which is connected to the rear ends of said draft-rods and the other 70 to the object to be moved; and a tackle-cable, all coacting for the purpose specified.

17. In a windlass, the combination of a supporting-frame; a scraper carried thereby; a transversely-arranged axle; a driving-wheel, 80 having a groove in the periphery thereof, mounted on said axle; winding-drums on said axle, to each side of said wheel; a driving-cable for said driving-wheel; a guide for said cable supported on said frame opposite said wheel; draft-rods secured to the sides of said frame; a draft-chain secured to the forward 85 ends of said draft-rods; means for detachably connecting said chains; an anchor-chain; a tackle consisting of a pair of pulley-blocks, one of which is connected to the rear ends of said draft-rods and the other to the object to be moved; a tackle-cable; and a vertical guide- 90 roller arranged in said frame opposite said driving-wheel to prevent the tackle-cables from being drawn across the edges of said wheel, all coacting for the purpose specified.

18. In a windlass, the combination of a supporting-frame; a scraper carried thereby; a transversely-arranged axle; a driving-wheel, 100 having a groove in the periphery thereof, mounted on said axle; winding-drums on said axle, to each side of said wheel; a driving-cable for said driving-wheel; draft-rods secured to the sides of said frame; a draft-chain secured to the forward ends of said draft-rods; means for detachably connecting said chains; an anchor-chain; a tackle consisting of a pair of pulley-blocks, one of which is connected to the rear ends of said draft-rods and the other to the object to be moved; a tackle-cable; and a vertical guide- 105 roller arranged in said frame opposite said driving-wheel to prevent the tackle-cables from being drawn across the edges of said wheel, all coacting for the purpose specified.

19. In a windlass, the combination of a supporting-frame; a scraper carried thereby; a transversely-arranged axle; a driving-wheel, 115 having a groove in the periphery thereof, mounted on said axle; winding-drums on said axle to each side of said wheel; a driving-cable for said driving-wheel; a guide for said

cable supported on said frame opposite said wheel; draft-rods secured to the sides of said frame; a draft-chain secured to the forward ends of said draft-rods; means for detachably connecting said chains; an anchor-chain; a tackle consisting of a pair of pulley-blocks, one of which is connected to the rear ends of said draft-rods and the other to the object to be moved; and a tackle-cable, all coacting for the purpose specified.

20. In a windlass, the combination of a supporting-frame; a scraper carried thereby; a transversely-arranged axle; a driving-wheel, having a groove in the periphery thereof, mounted on said axle; winding-drums on said axle, to each side of said wheel; a driving-cable for said driving-wheel; draft-rods secured to the sides of said frame; a draft-chain secured to the forward ends of said draft-rods; means for detachably connecting said chains; an anchor-chain; a tackle consisting of a pair of pulley-blocks, one of which is connected to the rear ends of said draft-rods and the other to the object to be moved; and a tackle-cable, all coacting for the purpose specified.

21. In a windlass, the combination of a supporting-frame; a transversely-arranged axle; a driving-wheel, having a groove in the periphery thereof, mounted on said axle; winding-drums on said axle to each side of said wheel; a driving-cable for said driving-wheel; a guide for said cable supported on said frame opposite said wheel; draft-rods secured to the sides of said frame; a draft-chain secured to the forward ends of said draft-rods; means for detachably connecting said chains; an anchor-chain; a tackle consisting of a pair of pulley-blocks one of which is connected to the rear ends of said draft-rods and the other to the object to be moved; and a tackle-cable, all coacting for the purpose specified.

22. In a windlass, the combination of a supporting-frame; a transversely-arranged axle; a driving-wheel, having a groove in the periphery thereof, mounted on said axle; winding-drums on said axle to each side of said wheel; a driving-cable for said driving-wheel; draft-rods secured to the sides of said frame; a draft-chain secured to the forward ends of said draft-rods; means for detachably connecting said chains; an anchor-chain; a tackle consisting of a pair of pulley-blocks, one of which is connected to the rear ends of said draft-rods and the other to the object to be moved; a tackle-cable; and a vertical guide-roller arranged in said frame opposite said driving-wheel to prevent the tackle-cables from being drawn across the edges of said wheel, all coacting for the purpose specified.

23. In a windlass, the combination of a supporting-frame; a transversely-arranged axle;

a driving-wheel, having a groove in the periphery thereof, mounted on said axle; winding-drums on said axle, to each side of said wheel; a driving-cable for said driving-wheel; a guide for said cable supported on said frame opposite said wheel; draft-rods secured to the sides of said frame; a draft-chain secured to the forward ends of said draft-rods; means for detachably connecting said chains; an anchor-chain; a tackle consisting of a pair of pulley-blocks one of which is connected to the rear ends of said draft-rods, and the other to the object to be moved; a tackle-cable; and a vertical guide-roller arranged in said frame opposite said driving-wheel to prevent the tackle-cables from being drawn across the edges of said wheel, all coacting for the purpose specified.

24. In a windlass, the combination of a supporting-frame; a transversely-arranged axle; a driving-wheel, having a groove in the periphery thereof, mounted on said axle; winding-drums on said axle to each side of said wheel; a driving-cable for said driving-wheel; draft-rods secured to the sides of said frame; a draft-chain secured to the forward ends of said draft-rods; means for detachably connecting said chains; an anchor-chain; a tackle, consisting of a pair of pulley-blocks one of which is connected to the rear ends of said draft-rods and the other to the object to be moved; and a tackle-cable, all coacting for the purpose specified.

25. In a windlass, the combination of a supporting-frame; a scraper carried thereby; a transversely-arranged axle; a driving-wheel, having a peripheral groove, mounted on said axle; winding-drums on said axle to each side of said wheel; a driving-cable for said driving-wheel; a draft-chain; a grappling-hook for the said draft-chain; an anchor-chain; and a cross-chain to which said anchor-chain is secured by a suitable pulley, for the purpose specified.

26. In a windlass, the combination of a supporting-frame; a scraper carried thereby; a transversely-arranged axle; a driving-wheel, having a peripheral groove, mounted on said axle; winding-drums on said axle to each side of said wheel; a driving-cable for said driving-wheel; a draft-chain; a grappling-hook for the said draft-chain; an anchor-chain; for the purpose specified.

27. In a windlass, the combination of a supporting-frame; a scraper carried thereby; a transversely-arranged axle; a driving-wheel, having a peripheral groove, mounted on said axle; winding-drums on said axle to each side of said wheel; a driving-cable for said driving-wheel; a draft-chain; an anchor-chain; means for detachably connecting said chains; and a cross-chain to which said anchor-chain is secured by a suitable pulley, for the purpose specified.

28. In a windlass, the combination of a supporting-frame; a scraper carried thereby; a

transversely-arranged axle; a driving-wheel, having a peripheral groove, mounted on said axle; winding-drums on said axle to each side of said wheel; a driving-cable for said driving-wheel; a draft-chain; an anchor-chain; and means for detachably connecting said chains, for the purpose specified.

29. In a windlass, the combination of a supporting-frame; a transversely-arranged axle; a driving-wheel, having a peripheral groove, mounted on said axle; winding-drums on said axle to each side of said wheel; a driving-cable for said driving-wheel; a draft-chain for said supporting-frame; a grappling-hook for the said draft-chain; an anchor-chain; and a cross-chain to which said anchor-chain is secured by a suitable pulley, for the purpose specified.

30. In a windlass, the combination of a supporting-frame; a transversely-arranged axle; a driving-wheel, having a peripheral groove, mounted on said axle; winding-drums on said axle to each side of said wheel; a driving-cable for said driving-wheel; a draft-chain for said supporting-frame; a grappling-hook for the said draft-chain; an anchor-chain, for the purpose specified.

31. In a windlass, the combination of a supporting-frame; a transversely-arranged axle; a driving-wheel, having a peripheral groove, mounted on said axle; winding-drums on said axle to each side of said wheel; a driving-cable for said driving-wheel; a draft-chain for said supporting-frame; an anchor-chain; means for detachably connecting said chains; and a cross-chain to which said anchor-chain is secured by a suitable pulley, for the purpose specified.

32. In a windlass, the combination of a supporting-frame; a transversely-arranged axle; a driving-wheel, having a peripheral groove, mounted on said axle; winding-drums on said axle to each side of said wheel; a driving-cable for said driving-wheel; a draft-chain for said supporting-frame; an anchor-chain; and means for detachably connecting said chains, for the purpose specified.

33. In a windlass, the combination of a supporting-frame; an axle; a driving-wheel having a groove in its periphery, mounted on said axle; drums on said axle to each side of said wheel; a cable for said driving-wheel; a guide for the said cable supported on said frame opposite said wheel; a tackle consisting of a pulley-block F having a sheave f on its rear end and a pair of sheaves f' at the sides thereof; a pulley-block G having sheaves g and g' arranged in pairs at the sides thereof; a tackle-cable L passed over said sheave f of the block F, thence rearwardly over the sheaves g' of the block G, thence forwardly over the sheaves g' of the block G, thence forwardly over the sheaves f' of the block F, thence rearwardly over the sheaves g of the block G, and thence forwardly to the winding-drums at each side of the driving-wheel, said pulley-blocks being of a greater width than said wheel; all coacting for the purpose specified.

34. In a windlass, the combination of a supporting-frame; an axle; a driving-wheel having a groove in its periphery mounted on said axle; drums on said axle to each side of said wheel; a cable for said driving-wheel; a tackle consisting of a pulley-block F having a sheave f on its rear end and a pair of sheaves f' at the sides thereof; a pulley-block G having sheaves g and g' arranged in pairs at the sides thereof; a tackle-cable L passed over the said sheave f of the block F, thence rearwardly over the sheaves g' of the block G, thence forwardly over the sheaves f' of the block F, thence rearwardly over the sheaves g of the block G, and thence forwardly to the winding-drums at each side of the driving-wheel, all coacting for the purpose specified.

34. In a windlass, the combination of a supporting-frame; an axle; a driving-wheel having a groove in its periphery mounted on said axle; drums on said axle to each side of said wheel; a cable for said driving-wheel; a tackle consisting of a pulley-block F having a sheave f on its rear end and a pair of sheaves f' at the sides thereof; a pulley-block G having sheaves g and g' arranged in pairs at the sides thereof; a tackle-cable L passed over the said sheave f of the block F, thence rearwardly over the sheaves g' of the block G, thence forwardly over the sheaves f' of the block F, thence rearwardly over the sheaves g of the block G, and thence forwardly to the winding-drums at each side of the driving-wheel, all coacting for the purpose specified.

35. In a windlass, the combination of a supporting-frame; an axle; a driving-wheel having a groove in its periphery mounted on said axle; drums on said axle to each side of said wheel; a cable for said driving-wheel; a guide for the said cable supported on said frame opposite said wheel; a tackle consisting of a pulley-block F having a sheave f on its rear end and a pair of sheaves f' at the sides thereof; a pulley-block G having sheaves g and g' arranged in pairs at the sides thereof; a tackle-cable L passed over said sheave f of the block F, thence rearwardly over the sheaves g' of the block G, thence forwardly over the sheaves f' of the block F, thence rearwardly over the sheaves g of the block G, and thence forwardly to the winding-drums at each side of the driving-wheel, said pulley-blocks being of greater width than said wheel; all coacting for the purpose specified.

36. In a windlass, the combination of a supporting-frame; an axle; a driving-wheel having a groove in its periphery mounted on said axle; drums on said axle to each side of said wheel; a cable for said driving-wheel; a tackle consisting of a pulley-block F having a sheave f on its rear end and a pair of sheaves f' at the sides thereof; a pulley-block G having sheaves g and g' arranged in pairs at the sides thereof; a tackle-cable L passed over said sheave f of the block F, thence rearwardly over the sheaves g' of the block G, thence forwardly over the sheaves f' of the block F, thence rearwardly over the sheaves g of the block G, and thence forwardly to the winding-drums at each side of the driving-wheel, said pulley-blocks being of a greater width than said wheel; all coacting for the purpose specified.

37. In a windlass, the combination of a supporting-frame; a scraper carried thereby; a winding-drum; a draft-chain secured to said frame; a claw-shaped grappling-hook for said draft-chain; an anchor-chain; a cross-chain to which said anchor-chain is secured by a suitable pulley; and a suitable tackle, coacting for the purpose specified.

38. In a windlass, the combination of a supporting-frame; a scraper carried thereby; a winding-drum; a draft-chain secured to said frame; an anchor-chain; means for detachably connecting said chains; a cross-chain to which said anchor-chain is secured by a suitable pulley; and a suitable tackle, coacting for the purpose specified.

39. In a windlass, the combination of a supporting-frame; a scraper carried thereby; a winding-drum; a draft-chain secured to said frame; a claw-shaped grappling-hook for said draft-chain; an anchor-chain; and a suitable tackle, coacting for the purpose specified.

40. In a windlass, the combination of a supporting-frame; a scraper carried thereby; a winding-drum; a draft-chain secured to said frame; an anchor-chain; means for detachably connecting said chains; and a suitable tackle, coacting for the purpose specified.

41. In a windlass, the combination of a frame; an axle; a drum on said axle; a driving-wheel on said axle; a cable; holes through said wheel adapted to receive said cable which is passed through three—at least—of said holes and its end slipped under the loop formed in said cable thereby, so that it is clamped by said loop against the face of the wheel, as specified.

In witness whereof I have hereunto set my hand in the presence of two witnesses.

JASPER A. WOODWORTH.

Witnesses:

ETHEL A. TELLER,
OTIS A. EARL.
